INVENTOR,
SIDNEY RICHARDSON
BY *Martin P. Smith* ATTY.

UNITED STATES PATENT OFFICE

2,045,025

METHOD OF PRODUCING ORTHODONTIC
BAND BRACKETS

Sidney Richardson, Hollywood, Calif., assignor
of one-half to Charles Edward Boyd, Los Angeles, Calif.

Original application August 17, 1934, Serial No. 614,703, now Patent No. 1,976,441, dated October 9, 1934. Divided and this application September 10, 1934, Serial No. 743,422

3 Claims. (Cl. 29—160.6)

My invention relates generally to the art of correcting the position of malposed teeth of the dental arch and more particularly to the method of construction and production of the brackets 5 that are attached to the tooth engaging bands and which brackets are constructed and shaped so as to conveniently receive the arch bars, ligatures and wires that are utilized for imparting the desired stresses and strains to the teeth that 10 are to be rotated or moved to the proper or desired positions with respect to the other teeth of the dental arch.

It will be understood that orthodontic appliances of the character to which my invention 15 relates and particularly the brackets that are applied to the tooth bands, are relatively small in size and that said brackets are subjected to considerable strains and stresses while in service and it is one of the principal objects of my invention to provide a method of producing brackets 20 so that the inherent strength of the metal of which said brackets are formed, is utilized to the maximum degree in resisting the strains and stresses that are impressed upon the brackets 25 while the same are in service.

A further object of my invention is, to provide a method of producing orthodontic tooth band brackets having great strength and rigidity 30 and the metal therein being disposed so as to resist to a maximum degree the tendency of the arch bar to rotate within the slot that is formed in the bracket for the reception of said arch bar.

A further object of my invention is, to provide 35 an improved method of forming orthodontic brackets so that the same will not yield and bend to such a degree as to permit the arch bar receiving notch to open or spread apart under torsional stresses imparted to said bracket by the arch bar that passes through the notch therein or as a result of tilting movement of the bracket 40 itself as a result of movement of the tooth that is engaged by the band that carries said bracket.

This application is a division of an application 45 for U. S. Letters Patent on Method of producing orthodontic band brackets filed by me June 1st, 1932, Serial No. 614,703 and allowed August 17, 1934.

With the foregoing and other objects in view 50 my invention consists in certain novel methods of construction and arrangement of parts that will be hereinafter more fully described and claimed and illustrated in the accompanying drawing in which:

55 Fig. 1 is a perspective view of a metal bar from

which certain forms of my improved bracket are formed.

Fig. 2 is a perspective view of the bar after the same has been provided with a slot in accordance with my improved method.

Fig. 3 is a perspective view of a section of the slotted bar cut to the proper length for the production of an arch bar receiving bracket.

Fig. 4 is a perspective view of an arch bar receiving bracket constructed in accordance with 10 my improved method.

Fig. 5 is a perspective view of a modified form of the bracket.

Fig. 6 is a vertical section taken on the line 6—6 of Fig. 5.

Fig. 7 is a perspective view of a further modified form of the bracket constructed in accordance with my method.

In the construction of the form of bracket illustrated in Fig. 4, I employ a block or bar 20 10 of alloy or platinized metal that is extremely hard and tough, said block or bar being substantially rectangular in cross section and having a flat rear face 11, parallel side faces 12 and a curved front face 13 that is transversely convex. 25

By means of a suitable cutting tool a longitudinally disposed slot 14 is formed in the block or bar 10, said slot being disposed midway between and parallel with the side faces 12 of the bar and said slot extends from the rear face 30 11 toward the front face 13.

The slotted bar is now divided into sections of suitable length, one of which sections is illustrated in Fig. 3 and the upper rear corners of the block or section to the sides of the slot 14 35 therein, are cut away to form a horizontally disposed notch 15 for the reception of the arch bar that is supported by and connected to the bracket. When this bracket is applied to the tooth band, the rear face of the bracket or those faces 40 below the notch 15 and to the sides of the slot 14, are soldered or brazed directly to the tooth band and thus a very strong and substantial bracket is provided for the support and attachment of the arch bar.

Where brackets of the type illustrated in Fig. 5 are produced by my improved method, the bar or block 10 is divided into sections that are slightly longer than the sections utilized for producing brackets of the type illustrated in Fig. 4 and 50 after the brackets have been notched for the reception of the arch bar, a narrow horizontally disposed slot such as 16, is formed in the lower portion of the bracket, said notch extending rearwardly from the curved front face of the bracket 55

and which notch or slot is for the accommodation of ligatures or the like.

Brackets of the form illustrated in Fig. 7, may be constructed by my improved method and in this form of bracket the horizontally disposed notch 16^a that is formed in the lower front portion of the bracket is made of sufficient width to receive an arch bar or the like.

In the forms of brackets illustrated in Figs. 5, 10 6, and 7, the rear ends of the slots or notches 16 and 16^a terminate a sufficient distance away from the rear face of the bracket so as to provide a base or body 17 of substantial thickness and which combines with those portions of the bracket immediately above and below the inner ends of the slots or notches 16 and 16^a to form a strong and substantial base for the bracket and as a result of this strong and substantial construction, the same will not tend to spread or 15 open as a result of torsional strains between the bracket and the arch bow or ligature that is positioned in the transverse slot or notch 16 or 16^a.

Inasmuch as my improved method contemplates the cutting of the brackets from solid blocks of metal, the molecules and fibres of the metal in all parts of the finished bracket retain their original relative positions, thus insuring the greatest possible strength of the metal that is utilized for forming the brackets and likewise the greatest 30 possible resistivity to strains and stresses that are developed while the brackets are in service.

In all cases the base or rear portions of the brackets and particularly those portions to the rear of the transverse notches that are formed in the front portions of the brackets, are made of substantial thickness, thereby imparting to the brackets the requisite strength to resist torsional strains that would otherwise tend to spread the jaws of the bracket apart and at the same time the relatively strong heavy base portions of the brackets serve to reenforce the tooth bands to which the brackets are braced or soldered and thereby provide an attachment of increased strength and stability.

The machining or cutting of the bracket from a solid block of metal eliminates the necessity for bending any portion of the bracket during its production and which bending it will be understood necessarily disturbs, stretches, expands and in some instances fractures the metal at the bending points with the result that the finished structure is materially weakened and it fails to produce the expected and desired results when applied for use.

The size of brackets utilized on tooth bands of orthodontic appliances precludes the possibility of their being successfully manufactured by dies and I have demonstrated in tests and experiments that dies, though very carefully constructed, cannot impart the necessary accuracy to the finished product, particularly in the formation of the notches that receive the arch wires, ligatures and the like.

I have demonstrated in practice that where metal is bent in the production of orthodontic brackets and particularly relatively hard and tough metal, there is a tendency of the bent portion of the metal to fracture and the grains or molecules of the metal separate, so that the bent portion becomes porous and thereby loses its strength and resistivity to service strains and stresses.

Orthodontic brackets constructed in accordance

with my improved method are exceptionally strong and rigid, serve to reenforce the tooth band to which they are soldered or brazed and as said brackets are formed from solid blocks of metal they are not bent during manufacture, the maximum strength of the metal forming the brackets is utilized to the greatest advantage in resisting tendency of the jaws of the brackets to open as a result of relative torsional strains between the brackets and the arch wires that are applied thereto.

It will be understood that minor variations in the method of constructing the various parts of my improved orthodontic band bracket may be practiced without departing from the spirit of the invention, the scope of which is set forth in the appended claims.

I claim as my invention:

1. The herein described method of producing a one-piece orthodontic band bracket, which consists in cutting a longitudinally disposed slot in the rear portion of a block of hard tough metal, which slot extends from the rear face of said block toward the front face thereof, cutting away the upper rear corner of the block of metal so as to form notches to the sides of the slot, cutting a horizontally disposed transverse slot in the lower front portion of the body of the block, which slot intersects the longitudinally disposed slot that is formed in said block, and the cutting of the block to form said slots and notches being effected so as to retain the fibers and molecules in the uncut portions of said block in their original positions without distorting and stretching the same.

2. The herein described method of producing a one-piece orthodontic band bracket, which consists in cutting a longitudinally disposed slot in the rear portion of a bar or elongated block of hard tough metal, which slot extends from the rear face of said bar toward the front face thereof, then cutting said bar to form a plurality of short sections that are substantially uniform in length, cutting the upper rear corner of each block away to form a pair of transversely disposed notches to the sides of the slot in the upper rear portion of the block, cutting a horizontally disposed transverse slot in the lower front portion of the block, which slot intersects the longitudinally disposed slot in the rear portion of said block, the cutting of said bar and block in each instance being effected so as to retain the fibers and molecules in the uncut portion of said bar and block in their original positions without distorting and stretching the same.

3. The herein described method of producing a one piece automatic band bracket, which consists in cutting a longitudinally disposed slot in the rear portion of a bar of hard tough metal, which slot extends from the rear face of said bar toward the front face thereof, then cutting said bar to form a plurality of blocks that are substantially uniform in length, cutting the upper rear corner of each block away to form a pair of transversely disposed notches to the sides of the slot in the rear portion of the block and the cutting of said bar and said blocks to form said slot and notches, being effected so as to retain the fibers and molecules in the uncut portions of the metal in their original positions without distorting or stretching the same.

SIDNEY RICHARDSON.

CERTIFICATE OF CORRECTION.

Patent No. 2,045,025.

June 23, 1936.

SIDNEY RICHARDSON.

It is hereby certified that error appears in the above numbered patent requiring correction as follows: In the heading to the printed specification, line 7, for the filing date "August 17, 1934" read June 1, 1932; and line 8, for "Patent No. 1,976,441" read Patent No. 1,976,141; and that the said Letters Patent should be read with these corrections therein that the same may conform to the record of the case in the Patent Office.

Signed and sealed this 22nd day of September, A. D. 1936.
